UNITED STATES PATENT OFFICE.

JOHN H. AKIN, OF SUMNER, MISSOURI.

RAILWAY-TIE.

1,069,637.

Specification of Letters Patent.

Patented Aug. 5, 1913.

Application filed April 4, 1912, Serial No. 688,541. Renewed February 5, 1913. Serial No. 746,418.

To all whom it may concern:

Be it known that I, JOHN H. AKIN, a citizen of the United States, residing at Sumner, in the county of Chariton and State of Missouri, have invented certain new and useful Improvements in Railway-Ties; and I do hereby declare the following to be a full, clear, and exact description of the invention, such as will enable others skilled in the art to which it appertains to make and use the same.

This invention relates to railroad ties; and it more particularly relates to certain improvements in the construction of metal ties and means combined therewith for securing them to railroad rails of ordinary construction.

An object of the invention is to provide a railroad tie of this character with improved and easily accessible means for securing its several elements together and to the rails.

A further object of the invention is to provide an improved supporting member or bridge, for connecting adjacent ties of this character, and for supporting the rail between the ties.

A further object is to reinforce certain portions of the ties, and to generally improve ties of this character.

A still further object is to provide a rail supporting bridge of such character that all of its parts may be easily accessible for applying paint or other anti-rust material.

Other objects and advantages will be hereinafter more clearly set forth and pointed out in the specification and claims.

In the accompanying drawings which form a part of this application, Figure 1 is a plan view, showing fragments of two railway track rails clamped in position by means of one of my improved railroad ties. Fig. 2 shows an elevation of the same. Fig. 3 is a vertical sectional view taken on line 3—3 of Fig. 1. Fig. 4 is a fragmental detail view of one of the clamping members. Fig. 5 is a perspective view of a combined washer and clamping member. Fig. 6 is a plan view of a somewhat modified construction, embodying the invention. Fig. 7 is a plan view of another modified form. Fig. 8 is a perspective view of a combined draw-bar and binder, employed in the modified form shown in Fig. 6. Fig. 9 is a combined washer and binder to be used in connection with the member shown in Fig. 8. Fig. 10 is a perspective view of a key-clip or binder

to be used in the construction shown in Fig. 7, and, Fig. 11 is a key to be used in connection with the member shown in Fig. 10.

Referring to Figs. 1, 2 and 3 of the drawings in which similar reference characters designate corresponding parts throughout the several views, the body of the tie comprises two angle-irons, or L-shaped members 15 and 16, each having a horizontal base 65 flange 17 and having vertical flanges 18 and 19 respectively. The vertical flanges 19 are provided with elongated slots 20, the flanges 18 having apertures registering with said slots, bolts 21 being seated in the slots and 70 apertures, for securing the flanges 18 and 19 together. The flanges 18 and 19 are formed with rail seats or recesses 22 and 23, respectively, and with retaining lugs 24 and 25, respectively, adjacent to or formed by 75 the apertures. The top portions of the vertical flanges have a reinforcing rib 26, whereby the retaining lugs, as well as the other top portions of the vertical flange are strengthened. The upstanding flanges are 80 each formed with a longitudinal and horizontal semi-circular or concavo-convexed portion consisting of a rib or ridge 27 and a semi-circular groove 28, on opposite sides of the vertical flange, above the slots 20, or 85 between said slots and the reinforcing ribs 26. When the base members 15 and 16 are secured together by the bolts 21, as shown, the grooves 28 register and form a cylindrical opening or housing between said 90 flanges, and from end to end thereof for receiving a draw-bolt 29, provided with a hooked end portion 30 having parallel sides 31 and 32. The bolt 29 is also provided with a nut 33 and has a washer 34 fitted 95 thereon, said washer having two parallel arms 35 and 36, the latter being the longer. Seated upon the flanges 17 is a substantially T-shaped support or bridge 37 having upstanding flanges 38 on its lateral extremities, thereby forming a trough or rail-seat 39, between said flanges, said rail-seat being on the same horizontal plane with the bottoms of the recesses 22 and 23, of the flanges 18 and 19. The middle stem or web 100 of the T-shaped rail 37 is directly under the web 40' of the railroad rail, and thereby provides a more solid support than is provided by otherwise constructed bridges for 105 this purpose.

In assembling the several elements of the tie, and applying the rails thereto, the bolt

29 is fitted into the grooves 28, the hooked end portion 30 engaging the end of the flange 19, which extends beyond the adjacent end of the flange 18. The washer 34 is then 5 applied against the end of the flange 18 which extends beyond the adjacent end of the flange 19, the long arm 36 of said washer resting against the end of the flange 19, the short arm 35 embracing the end of the flange 10 18, so that the adjacent ends of the flanges are held firmly together by means of said washer and said hooked end of the bolt 29. Up to this time, the bolts 21 have not been 15 tightened, but merely hold the flanges 18 and 19 together in slidable relation, so that when the nut 23 is tightened on the bolt, the members 15 and 16 are thereby caused to move in opposite directions, so that the retaining lugs 24 and 25 are brought into contact with 20 the top of the base-flange 40 of the track-rail, and retain said rail firmly within the trough or seat 39. In thus moving the flanges by means of the members 29 and 33, it will be seen that if a washer of ordinary 25 construction were employed instead of the washer 34, there would be a tendency for said washer to leave the flange 18, and in doing so, to bend the bolt 29 and to force the flange 18 away from the flange 19, in an obvious manner; but, by providing the arms 30 35 and 36, on said washer 34, the arm 35 prevents lateral movement of the bolt, while the arm 36 prevents the washer 34 from becoming diagonally disposed relative to the bolt 35 29. That is, the arms 35 and 36 serve to hold the washer at right angles to the axis of the bolt, and at the same time, to retain the adjacent ends of the flanges together. The purpose and operation of the hooked 40 end 30 of the bolt are similar to those described for the washer member 34.

By this construction, it will be seen that while the base portion of the tie is held firmly together by the bolts 21, the upper 45 portion is held together by means of the bolt 29 and its adjuncts. It will also be obvious that, by this construction, the bolt 29 and nut 33 are elevated above the railroad bed sufficiently to allow convenient access thereto, when it is desirable to place, remove or 50 replace a tie of this construction. It is obvious that the ribs or ridges 27 render the flanges 18 and 19 more rigid than where such ribs are omitted, as well as to compensate for the loss of material consequent to 55 the grooves 28. However, my invention does not essentially depend on the exact details of construction, as described, and I have therefore shown in Figs. 6 and 7 certain modifications 60 which do not materially depart from the embodiment of the invention already described. In these modifications, the ridge 27 and groove 28 are eliminated, and in lieu of the draw-bolt 29 I provide a shorter draw-bolt 29^a, the hooked end or binder 30^a of this

shorter bolt being relatively thin and wide, so that it may be inserted into the slots 41 and 42, through the vertical flanges 18^a and 19^a. The bolt 29^a is fitted with a nut 33^a, which is seated on a combined washer and binder 34^a having an arm 35^a and a relatively long arm 36^a, the latter being provided with a semi-cylindrical groove 36^b and provided with a cylindrical bore 36^c communicating with said semi-cylindrical groove. 70 75 This washer member is seated on the draw-bolt 29^a, which passes through the cylindrical bore and fits snugly in the semi-cylindrical groove, while the arm 35^a engages the end of the flange 19^a and coacts with the hooked end or binder member of the bolt 29^a for holding the adjacent ends of the flanges 18^a and 19^a together. It will be seen that the arms 35^a and 36^a operate in the manner described for the flanges 35 and 36. Obviously, as the flanges 18^a and 19^a are moved into engagement with the track-rail flanges 40, as described in connection with Figs. 1, 2 and 3, the bolts 21 are moved along within the slots 20, and when the flanges 18^a and 19^a have reached the limit of their movement, the bolts 21 may then be tightened, so that they will coact with the bolt 29 or 29^a, for retaining the several members in fixed relation to each other. 90 95

As shown by Figs. 7, 10 and 11, I may employ, in lieu of bolts, keys or wedges 43 each of which coacts with a two-arm key-clip 44, having an arm 45 and a relatively long arm 46, said arms being spaced apart 100 equal to the combined thickness of the vertical flanges 18^b and 19^b and embracing said flanges therebetween; said key-clip or binder member, being in the shape of an L, the base of which is at right angles to the flanges 18^b and 19^b and forms a seat for the key 43. The flanges 18^b and 19^b are provided with apertures 41 and 42 through which the key 43 and key-clip 44 extend. It is obvious that when desirable to move the flanges 18^b and 19^b, for engagement with the rail flanges 40, it is only necessary to insert the wedge-shaped key 43 and drive it to the position shown in Fig. 7, whereby it will coact with said flanges and with the key-clip for thus 110 moving the vertical flanges, and for holding them in the desired fixed position. 115

It will be seen that in these several embodiments of my invention, I have provided a very substantial means of supporting and securing railroad rails upon the railroad bed, that because of the wide base of these ties, the number required per mile of railroad may be very greatly decreased without decreasing the supporting efficiency of the 125 railroad, since the bridges 37 support the track rails between said ties.

I do not limit my invention to the exact details of construction, combination and arrangement of parts herewith described and 130

shown; but, my invention may only be limited by a reasonable interpretation of the following claims.

What I claim is:

- 5 1. In a metal railway tie, a tie body consisting of a pair of angle irons, each angle iron being formed with a longitudinal concavo-convexed portion, means securing the concavo-convexed portions into registration and thereby forming a housing, and a bolt seated in the housing and coöperating with the angle irons for securing a railway rail thereto.
- 10 2. In a metal railway tie, a body consisting of a pair of angle irons fitted together so as to form a pair of upstanding flanges and a pair of horizontal flanges, said upstanding flanges being formed with registering concavo-convexed portions which form a cylindrical housing, means engaging the upstanding flanges between the housing and the horizontal flanges for securing the angle irons together, and means within said housing for effecting engagement of the upstanding flanges with a railway rail.
- 15 3. In a metal railway tie, a tie body consisting of a pair of angle irons having upstanding flanges movably secured together and having rail engaging means thereon and having registering apertures therethrough, a 30 hooked and screw-threaded bolt extending through the apertures and embracing the opposite sides of the respective flanges, a combined washer and binder having an aperture and being provided with a groove communicating with the aperture, said bolt being seated in the groove and aperture, said washer and binder being provided with an arm for engaging an end of one of the upstanding flanges, and means coacting with 35 the bolt and combined washer and binder for effecting engagement of the flanges with the rails.

In testimony whereof I have signed my name to this specification in the presence of 40 two subscribing witnesses.

JOHN H. AKIN.
